FORCED CIRCULATION STEAM GENERATOR

Ward S. Patterson, Chappaqua, N. Y., assignor to
Combustion Engineering-Superheater, Inc., a
corporation of Delaware

Application September 4, 1947, Serial No. 772,149

6 Claims. (Cl. 122—411)

1

This invention relates to apparatus for generating steam and particularly to a steam generator in which there is a controlled forced circulation of the fluid through the steam generating tubes.

In steam generators constructed to operate in this manner it is essential to distribute the water to the steam generating tubes in sufficient quantity so that each of the tubes, which are arranged for parallel water flow therethrough, will be sufficiently cooled by the water to protect it against overheating and consequent damage under all rates of steaming.

A preferred way of accomplishing such desirable distribution of water to all of the tube circuits which are connected for parallel water flow therethrough to a manifold or distribution header, has been to provide orifices or resistances at the entrance to each of the tubes. These orifices are of smaller diameter than the tube, the diameter being chosen to present a substantial resistance to the flow of water. Variations in the latter resistance then have a reduced influence upon the total resistance of orifice and tube and consequently upon the flow of water through the tube as governed by the orifice.

It is essential then that the orifice remain unobstructed by foreign matter such as scale particles or sludge, during operation because the amount of water flow through the tube and the tube's safety depend upon it. Heretofore screens or strainers have been provided within the distribution header at each of the orifices, whose screen openings are smaller than the orifice so as to stop the flow of foreign matter to the orifice which would otherwise obstruct it.

It has been found from experience that it is impossible to insure against predominant segregation of such foreign matter into some of the distribution headers and often to a limited location in one of the headers, as for example adjacent the ends or near the middle of a header, depending upon flow conditions in the header. The amount of the foreign matter or solid material in circulation within the steam generator may be insignificant yet sufficient, when segregated at one location within a header, to cause trouble. Such segregation has resulted in a local orifice strainer becoming plugged and failure of the associated tube from lack of water and overheating.

It is an object of this invention to provide an improved strainer within a distribution header which will overcome the above difficulties.

Referring to the drawings illustrating preferred embodiments of the invention:

Fig. 1 is a diagrammatic representation of a forced circulation steam generator.

Fig. 2 is an enlarged cross section through a

2

distribution header of Fig. 1 showing one form of the invention.

Fig. 3 is an enlarged cross section through a distribution header of Fig. 1 showing another form of the invention.

Figure 4 is a section taken on line 4—4 of Figure 1 showing how the steam generator's heat absorbing tubes are arranged for parallel flow therethrough of the liquid to be vaporized.

Fig. 5 is a longitudinal section through the steam generator's distribution header taken on line 5—5 of Figs. 2 and 3 and showing how the herein-disclosed screening means extend longitudinally of the header to span a multiplicity of steam generating tube ends.

Figures 1 and 4 illustrate an embodiment of the invention arranged for steam generation. The steam generator illustrated comprises a furnace chamber 1 within which fuel is burned by means such as an oil burner 2 arranged to deliver oil for combustion in the furnace in a well known manner. The boiler 3 having its heating surface 4 within the furnace comprises a horizontal cylindrical steam and water drum 5 to which water may be supplied from any suitable source through feed pipe 6 and steam may be withdrawn through pipe 7.

The heating surface 4 within the boiler comprises a multiplicity of parallelly-arranged tubes 4 connected to a common distribution header 8 and passing thence upwardly along a wall of the furnace 1 and thence in back-and-forth passes upwardly through the upper portion of the furnace to connect to the steam and water drum 5. A downcomer 9 is connected at its upper end to the bottom portion of drum 5 and at its lower end to the inlet of a circulation pump 10. The pump is connected at its discharge end to distribution header 8 by connection 11. The pump 10 is driven as by a motor (not shown) and circulates the water from drum 5 into header 8 thence through all of the tubes 4 and back into drum 5. An offtake 12 removes the products of combustion from the furnace.

In order to insure a proper distribution of the water among all of the tubes of the heating surface 4 which are connected in parallel between the header and drum, it is essential to provide means such as orifices 13 (as shown in Figs. 2 and 3) for restricting the flow of water at the entrance end of each tube. The present invention is concerned with an improved means for maintaining these orifices in proper operating condition by protecting them from foreign material in the water which might obstruct them.

Figs. 2 and 3 show two preferred embodiments of my invention as arranged within the distribution header 8 and 8' respectively. In Fig. 2 the distribution header 8 is rectangular in form having water supply tubes or pump connection

from circulation pump 10 as shown in Fig. 1. The steaming or boiler tubes 4 are connected to the header as by welding and are in alignment with a cylindrical opening 14 through wall 15' of distribution header 8'.

A semi-cylindrically shaped strainer 16' is mounted within the header 8 and comprises a semi-cylindrical plate 17 welded to a flat closure plate 18 extending across the diameter of the strainer 16'. Arranged centrally and longitudinally of the closure plate 18 are orifices 13 mounted into holes 19 provided in said plate longitudinally thereof at spaced intervals. The orifice structure comprises a tubular portion 20 having an outside diameter suitable for mounting in hole 19 in plate 18 and having an end portion 21 within which is the orifice opening 13. The cylindrical plate 17 of strainer 16' is provided with a multiplicity of apertures 22 each of which is smaller in diameter than the diameter of orifice hole 13. Preferably the sum of the areas of said perforations is at least 75% of the area of the unperforated strainer tube containing said orifices.

This strainer 16' is mounted on header wall 15' by means of stud bolts 23 projecting from said wall and bands 24 which bear against the strainer to urge it toward the header wall 15'. The strainer 16' is so placed that the orifice holes align with the respective ends of the tubes 4. Preferably a soft gasket 25 may be placed between the plate 18 of strainer 16' and the wall 15' of header 8'. Should the gasket 25 be omitted the strainer 16' would move into contact with the header wall 15' and the cylindrical portion 20 of the orifice would enter the hole 14 provided within the header wall 15' in alignment with tubes 4. The diameter of the strainer 16' is such that it may be removed through the hand hole 26 at the end of the header 8'.

The strainer of Fig. 3 (wherein like reference numbers indicate like parts as in Fig. 2) is in all essentials similar to the strainer in Fig. 2 excepting that this Fig. 3 strainer 16 now comprises a complete cylinder structure. A multiplicity of spaced-apart nozzles 27 are welded on to the strainer, one opposite each of the holes 14 in the header wall 15 (shown in Fig. 3 as being curved). The cylindrical portion 20 of the orifice structure is mounted into these nozzles and projects beyond the end of the nozzles to provide a seat for a possible soft gasket 25. Should the gasket be omitted the cylindrical portion 20 will telescope into the hole 14 in header wall 15 and the outer face of nozzle 27 will rest against the inner face of the header wall 15. The support of the strainer in Fig. 3 is identical with the support of the strainer shown in Fig. 2.

The strainers 16 and 16' of both the Fig. 2 and Fig. 3 designs may be made several feet long or any length that may be conveniently handled (see Fig. 5). Only two or three clamps per strainer are required so that only a few hand holes 28 will be required in header walls opposite to the strainer. With my improved strainer but eight or ten strainers are all that would be required for a large-sized steam generating unit when compared to the present requirement of three hundred to four hundred individual strainers adjacent each tube end. Furthermore, but twenty or thirty hand hole openings located opposite each strainer support will take the place of three hundred to four hundred closure plug openings as now used where one closure is required opposite the end of each tube.

With my improved strainer each orifice may receive its water through the adjacent apertures in the strainer or, should these adjacent apertures be plugged by foreign matter, said orifice could receive its water from apertures opposite the remaining orifices included by said strainer. In this manner the danger of obstructing one orifice with its individual strainer is overcome.

Furthermore, it is possible with my improved arrangement of strainer to provide two pressure taps in each header, one connected to the space outside of the strainers and the other to the space inside of the strainers, so that a pressure drop across the strainer may be noted which will give an indication of the degree of plugging. This is an improved feature for a boiler unit operating with high makeup of treated (non-evaporated) feed water.

While the preferred embodiment of my invention has been shown and described, it will be understood that changes in construction, combination and arrangement of parts may be made without departing from the spirit and scope of the invention as claimed.

What I claim is:

1. In a steam generator having a steam and water drum and a plurality of steam generating tubes exposed to the heat of the products of combustion from a furnace, a distribution header connected to the inlet ends of the aforesaid plurality of tubes for flow of water therethrough in parallel circuits, the discharge ends of said tube circuits being connected to the steam and water drum; resistance means within each circuit disposed at the said inlet end of each tube that is connected to said distribution header and in fluid-flow relationship therewith; screen means mounted within the header to prevent foreign matter from obstructing the resistance means, said screen means comprising a tubular perforate element extending longitudinally of the header to span a multiplicity of the steam generating tube ends and forming an envelope surrounding an open and unobstructed passage from any open portion of said tubular perforate element to any and all of said resistance means; means connecting each tube inlet end and its resistance means with the inner or discharge side of said tubular perforate element so that only water which has passed through the screen perforations can be admitted into the said resistance means for each tube; means for forcing a flow of water through the circuits in direction of from the drum to the header through the aforesaid tubular perforate element and tubes back to the drum; and connections from the steam and water drum to said forcing means and from said forcing means to that portion of the distribution header's interior which surrounds the outer or inlet side of said tubular perforate screening element.

2. In a steam generator having a steam and water drum and a plurality of steam generating tubes exposed to the heat of the products of combustion from an associated furnace, a distribution header connected to the inlet ends of the aforesaid plurality of tubes for flow of water therethrough in parallel circuits, the discharge ends of said tube circuits being connected to the steam and water drum; means forming an orifice within each circuit said means being disposed adjacent the said inlet end of each tube and in fluid-flow relationship therewith; a perforate wall element mounted within the header to pre-

vent foreign matter from obstructing the said orifice means, said perforate wall element having an inlet side and an outlet side and extending longitudinally of the header to span a multiplicity of the steam generating tube ends at said wall element's outlet side and being adapted to form an unobstructed passage to any and all of the aforesaid orifice means from any open portion of said perforate wall element so that only water which has passed through the perforate wall from its inlet side to its outlet side can be admitted into the aforesaid orifice for each tube; a pump for forcing a flow of water through the circuits in direction of from the drum to the header through the perforate wall and tubes back to the drum; and connections from the steam and water drum to the pump inlet and from the pump discharge to that portion of the distribution header which is on the inlet side of said perforate wall element.

3. In a steam generator having a steam and water drum and a plurality of steam generating tubes exposed to the heat of the products of combustion from a furnace, a distribution header connected to the inlet ends of the aforesaid plurality of tubes for flow of water therethrough in parallel circuits, the discharge ends of said tube circuits being connected to the steam and water drum; resistance means within each circuit disposed at the said inlet end of each tube that is connected to said distribution header; an access hole in an end of said header; screen means mounted within the header to prevent foreign matter from obstructing the resistance means and constructed to be removable through said hole, said screen means comprising a tubular perforate element extending longitudinally of the header to span a multiplicity of the steam generating tube ends; means connecting each tube inlet end with the inner or discharge side of said tubular screen so that only water which has been passed through the screen perforations can be admitted into the said resistance means for each tube; means for forcing a flow of water through the circuits in direction of from the drum to the header through the said tubular screen and tubes back to the drum; and connections from the steam and water drum to said forcing means and from said forcing means to that portion of the distribution header interior which surrounds the outer or inlet side of said tubular screen element.

4. In a steam generator having a steam and water drum and a plurality of steam generating tubes exposed to the heat of the products of combustion from a furnace, a distribution header connected to the inlet ends of the aforesaid plurality of tubes for flow of water therethrough in parallel circuits, the discharge ends of said tube circuits being connected to the steam and water drum; resistance means within each circuit disposed at the said inlet end of each tube that is connected to said distribution header; means forming a fluid-flow connection between each tube inlet end and the said resistance means thereat; an access hole in an end of said header; screen means mounted within the header to prevent foreign matter from obstructing the resistance means and constructed to be removable through said hole, said screen means comprising a perforated tubular member extending longitudinally of the header to span a multiplicity of

the steam generating tube ends and having an inner or discharge side connected with all of said tube end resistance means to establish unobstructed communication therewith; means for forcing a flow of water through the said plurality of circuits in direction of from the drum to the header through said perforate tubular member and tubes back to the drum so that only water which has passed through the tubular member's perforations can be admitted into the said resistance means for each tube; and connections from the steam and water drum to said forcing means and from said forcing means to that portion of the distribution header interior which surrounds the outer or inlet side of said perforate tubular member.

5. In a forced circulation boiler, the combination of a steam and water drum; a distributing header; a plurality of heat absorbing tubes for the generation of steam from water having outlet ends communicating with said steam and water drum and having inlet ends connected to a row of openings in said distributing header; flow restricting means associated with each of the said inlet ends of said tubes; forced circulation means having a suction side connected to said steam and water drum and a discharge side connected to said distributing header; and a perforated division wall within said header disposed in a position opposite the said row of tube inlet openings and interposed between the discharge side connection of said forced circulation means and the said row of tube inlet openings whereby water recirculated from said steam and water drum by way of said circulation means can enter any one of said heat absorbing tubes by passing through any one of the perforations of said header's division wall.

6. In a steam generating boiler, the combination of a steam and water drum; a distributing header; heat absorbing tubes for the generation of steam from water having discharge ends connected to said steam and water drum and having inlet ends connected to a row of openings in said distributing header; flow restricting means at the inlet end of each of said tubes; forced circulation means having a suction side connected to said steam and water drum and a discharge side connected to said distributing header; and a perforated strainer member within said header extending along the row of tube inlet openings from end to end thereof and interposed between the discharge side connection of said forced circulation means and the said row of heat absorbing tube inlet openings whereby water recirculated from said steam and water drum by way of said circulation means can enter any one of said heat absorbing tube inlet openings by passing through any one of the perforations of said header's strainer member.
